FOREIGN PATENT DOCUMENTS

WO WO2004071241 8/2004

Primary Examiner — Susan Moon Lee

(57) **CLAIM**

The ornamental design for a pet chair shopping cart insert, as shown and described.

DESCRIPTION

FIG. 1 is a front view of a pet chair shopping cart insert showing my new design;

FIG. 2 is a rear view of the pet chair shopping cart insert;

FIG. 3 is a right side view of the pet chair shopping cart insert, a left side view being a mirror image thereof;

FIG. 4 is a top view of the pet chair shopping cart insert, a bottom view being a mirror image thereof; and,

FIG. 5 is a front bottom side perspective view of the pet chair shopping cart insert.
